(57) CLAIM

The ornamental design for a baseball hat, as shown and described.

DESCRIPTION

FIG. 1 is a rear perspective view of a baseball hat;

FIG. 2 is a rear view thereof;

FIG. 3 is a front view thereof;

FIG. 4 is a side view thereof;

FIG. 5 is another side view thereof;

FIG. 6 is a top view thereof; and,

FIG. 7 is a bottom view thereof.

The broken lines radiating from the central top button of the baseball hat depict stitching that forms no part of the claimed design. The remaining broken lines depict portions of the baseball hat that form no part of the claimed design.

1 Claim, 6 Drawing Sheets

FIG. 1

FIG. 2FIG. 3FIG. 4

FIG. 5

FIG. 6

FIG. 7
